(57) **CLAIM**

The ornamental design for a steering wheel for a car and/or game controller, as shown and described.

DESCRIPTION

FIG. 1 is a front view of a steering wheel for a car and/or game controller showing my design thereof;

FIG. 2 is a left side view thereof;

FIG. 3 is a right side view thereof;

FIG. 4 is a bottom view thereof;

FIG. 5 is a top view thereof;

FIG. 6 is a rear view thereof;

FIG. 7 is a front view of a second embodiment of the steering wheel for a car and/or game controller showing my design thereof;

FIG. 8 is a left side view of FIG. 7;

FIG. 9 is a right side view of FIG. 7;

FIG. 10 is a bottom view of FIG. 7;

FIG. 11 is a top view of FIG. 7; and,

FIG. 12 is a rear view of FIG. 7.
